J. H. MARSH

YARN CLEARER AND CLEANER

Filed Sept. 26, 1922

Inventor :-

John Henry Brown

By his Attorney: John D. Currill

UNITED STATES PATENT OFFICE.

JOHN HENRY MARSH, OF SWINTON, MANCHESTER, ENGLAND.

YARN CLEARER AND CLEANER.

Application filed September 26, 1922. Serial No. 590,640.

To all whom it may concern:

Be it known that I, JOHN HENRY MARSH, subject of the King of Great Britain and Ireland, and resident of Swinton, Manchester, in the county of Lancaster, England, have invented an Improved Yarn Clearer and Cleaner, of which the following is a specification.

In clearing or cleaning apparatus for 10 yarns it is important that the pairs of clearer knives, whilst maintaining their efficiency for the removal of slubs, or foreign matter from the yarns, shall be capable of very accurate adjustment relatively to each 15 other, so that they may be adjusted to suit various kinds of yarn according to the quality or comparative cleanliness of the latter.

These improvements relate to such apparatus for clearing or cleaning yarn, and 20 have for object the provision of such an apparatus which shall be simple and will admit of ready and simultaneous adjustment of the clearing or cleaning means whilst at the same time ensuring that such means 25 shall maintain their efficiency in operation.

In carrying my invention into effect, I provide a clearer or cleaning apparatus comprising a rotatable shaft having circular clearer discs—hereinafter referred to as 20 knives—mounted thereon; a second shaft parallel to the first, also rotatable and with means for longitudinal adjustment of said shaft, and having mounted thereon circular clearer knives to co-act with the clearer 35 knives mounted on the first shaft. The second shaft is slideable longitudinally in its bearings, and the longitudinal adjustment thereof may be effected whilst still allowing of free rotation of the shaft, as will 40 be hereinafter shown.

The improvements will now be fully described with reference to the accompanying drawings, wherein:

Figure 1, is a plan of the complete apparatus.

Figure 2, is an elevation of same.

Figure 3, is a section on line 3—3 of Figure 2:

Figure 4, is a sectional view of the adjusting means for the second shaft above referred to; and Figure 5 a sectional view of an end bearing for the first shaft.

Referring to the drawings, Figures 1 and 2, 1 is the base of the apparatus, provided 55 with a side frame 2 formed with bearings

in which the necks of the various shafts are journalled as shown. 3 is a first motion shaft, journalled as indicated, and passing through and being supported by a bearing 4 as shown in Figure 1. It has keyed upon 60 it the face bevel 4^a, or other desired toothed wheels which may transmit action to the shaft 3 from any convenient source. The shaft 3 has keyed thereon the spur wheel 5 gearing with a spur wheel 6 on a further 65 shaft 7 parallel to the shaft 3, and this spur wheel 6 gears with a still further spur wheel 6^a on shaft 8 parallel to the other two shafts. The shafts 7 and 8 will be respectively referred to hereinafter as the first 70 clearer shaft and the second clearer shaft.

The first and second clearer shafts 7 and 8 are journalled as stated above in bearings in the side frame 2, and their other extremities are journalled in bearings 9, 10 75 in the opposite side frame 11. On each shaft 7 and 8 are mounted the clearer knives 12, 13, each knife being fitted upon its shaft in any convenient manner, as for instance by set screws passing through the collars 80 14, and the knives are so arranged relatively to each other that a clearer knife 12 upon shaft 7 overlaps the other clearer knife 13 upon shaft 8 as shown. Each knife is of truncated conical formation, the vertex of one conical knife forming with the vertex of the other conical knife of the pair, a passage through which the yarn passes. The surfaces of the knives are recessed at 85 15. It will be seen that when the shaft rotates, the shafts 7 and 8 will also rotate but in opposite directions the one to the other, and the adjacent annular faces of the clearer knives 12 and 13 form an effective clearing 90 device for yarns passing therebetween. 95

The second clearer shaft 8 is adapted to rotate only but the first clearer shaft is adapted to be adjusted longitudinally to adjust the distance between any knife 12 and the other knife 13 of a pair. The means for adjustment are shown in detail in Figure 4. In that figure, 7 is the shaft and 9 the journal or housing for the end thereof. Upon the shaft 7 is secured a collar 16, having a recessed face which with a correspondingly recessed face on a loose collar 17 forms a race for the balls 17^a. The housing is internally threaded at 18 to receive a threaded plug 19, which is centrally recessed at 20 to receive the single thrust 100 105 110

ball 21 supported in its recess by the shaft 7. A slot 22 is provided in the plug to enable it to be rotated by a suitable tool. Rotation of the plug 19 to force the shaft 7 to the left as shown in Figures 1 and 2 will bring any knife 12 closer to its corresponding knife 13, whilst the helical spring 23 abutting against the inner end of the bearing and against the collar 17 upon the shaft, keeps the latter in its adjusted positions, and a similar effect is obtained when the knives are separated by rotation of the adjusting plug. At the same time, the thrust ball bearing means allow for the rotation of the shaft 7.

The two shafts 7 and 8 are formed of the same metal and of the same length and diameter. They have therefore the same cubic content, and will expand and contract equally as a result of temperature changes, a very important consideration, as any motion in expansion or contraction as between the two shafts 7 and 8 would affect the distance between each of the knives of a pair as will be understood.

The particular relation of the shaft 7 and the spring 23 ensures that the said shaft will always maintain its position without longitudinal play. To prevent longitudinal motion of the second shaft 8 whilst the knives 13 mounted thereon are in operation and co-acting with the knives 12 on shaft 7, we may adopt the special thrust bearing shown in Figure 1 and to a larger scale in Figure 5. Referring specially to Figure 5, 8 is the shaft as before stated, 10 the bearing or housing, and 24 a collar secured upon the end of said shaft. Bearing balls 25 are interposed between the collar 24 and the end wall of the housing 10. A plug 26 is fitted within the housing, said plug being recessed as shown for the reception of a ball 27 which rests therein and bears against the end of the shaft 8 by the pressure upon the plug 26 of the helical spring 28 secured at one extremity to the said plug. The spring 28 bears, at its other extremity, against a screwed end plug or closer 29, and the latter by means of a suitable tool inserted in slot 30, may be manipulated to vary the pressure of the said spring if desired.

As a result of this construction no change can take place in the space between a pair of knives except that effected purposely by the adjustments of the plug 19, and with a thread of fine pitch it will be readily understood that such adjustments may be micrometric.

The knives 12, 13 need not necessarily be of the form described and shown. If desired, the adjacent faces of any pair may be plane; or the knives themselves may be circular plates, mounted in the relative positions shown.

Any suitable metal may be used for the

construction of the various parts—shafts 7 and 8 being of the same metal as before stated.

Although I have shown two pairs of knives only, it will be understood that any number of pairs may be mounted on the shafts 7 and 8, the gear wheels 5, 6 and 6^a being fitted on their respective shafts at any convenient point or points. Further, the shaft 3 and its accessories may be dispensed with and any suitable method adapted for driving the shaft 7, or the shaft 8 direct, these shafts being geared together as shown.

I claim:—

1. Apparatus for clearing and cleaning yarns, said apparatus comprising a rotary shaft, circular knives mounted upon the said shaft to rotate therewith, a second rotary shaft parallel to the first and having circular knives mounted thereon to rotate therewith, the periphery of any circular knife on one shaft overlapping the periphery of any circular knife on the other shaft, with a space for yarn to pass between the overlapping portions of the knives for the clearing or cleaning of said yarn, bearings for the shafts, and means for rotating the two shafts in opposite directions simultaneously.

2. Apparatus for clearing and cleaning yarns, said apparatus comprising a rotary shaft, circular knives mounted upon the said shaft to rotate therewith, a second rotary shaft parallel to the first and having circular knives mounted thereon to rotate therewith, any circular knife on one shaft overlapping the periphery of a circular knife on the other shaft and the adjacent faces of such a pair of knives being centrally recessed to form an annular face on each knife, with space between the overlapping portions of the knives for the passage of yarn, bearings for the two shafts, and means for rotating the two shafts in opposite directions simultaneously.

3. Apparatus for clearing and cleaning yarns, said apparatus comprising a rotary shaft, circular knives mounted upon the said shaft to rotate therewith, a second rotary shaft parallel to the first and having circular knives mounted thereon to rotate therewith, the periphery of any circular knife on one shaft overlapping the periphery of a circular knife on the other shaft with a space for yarn to pass between the overlapping portions of the knives for the clearing or cleaning of said yarn, bearings for the shafts, means for rotating the two shafts in opposite directions simultaneously, and means for longitudinal adjustment of one of the shafts to vary the space between any circular knife on said shaft and its co-acting knife on the other shaft.

4. Apparatus for clearing and cleaning yarns, said apparatus comprising a rotary shaft, circular knives mounted upon the said

- shaft to rotate therewith, a second rotary shaft parallel to the first and having circular knives mounted thereon to rotate therewith, the periphery of any circular knife on one shaft overlapping the periphery of a circular knife on the other shaft, with a space for yarn to pass between the overlapping portions of the knives for the clearing or cleaning of said yarn, bearings for the shafts, and means for rotating the two shafts in opposite directions simultaneously, both shafts being of the same material and of equal cubic content.
5. Apparatus for clearing and cleaning yarns, said apparatus comprising a rotary shaft, circular knives mounted upon the said shaft to rotate therewith, a second rotary shaft parallel to the first and having circular knives mounted thereon to rotate therewith, the periphery of any circular knife on one shaft overlapping the periphery of a circular knife on the other shaft with a space for yarn to pass between the overlapping portions of the knives for the clearing or cleaning of said yarn, bearings for the shafts, means for rotating the two shafts in opposite directions simultaneously, means for longitudinal adjustment of one on the shafts to vary the space between any circular knife on said shaft and its co-acting knife on the other shaft, a housing for one end of said other shaft, a collar on the end of said other shaft, and a spring controlled plug within the housing to press the said collar against the ball bearing fitted between itself and the inner wall of the housing to keep the shaft in position longitudinally whilst allowing of its free rotation.
- 10 15 20 25 30
6. Apparatus for clearing and cleaning yarns, said apparatus comprising a rotary shaft, circular knives mounted upon the said shaft to rotate therewith, a second rotary shaft parallel to the first and having circular knives mounted thereon to rotate therewith, the periphery of any circular knife on one shaft overlapping the periphery of a circular knife on the other shaft with a space for yarn to pass between the overlapping portions of the knives for the clearing or cleaning of said yarn, bearings for the shafts, means for rotating the two shafts in opposite directions simultaneously, means for longitudinal adjustment of one on the shafts to vary the space between any circular knife on said shaft and its co-acting knife on the other shaft, a housing for one end of said other shaft, a collar on the end of said other shaft, and a spring controlled plug within the housing to press the said collar against the ball bearing fitted between itself and the inner wall of the housing to keep the shaft in position longitudinally whilst allowing of its free rotation.
- 35 40 45 50 55 60

ment plug for adjusting the shaft longitudinally against the compression of the spring, and means for rotating the two shafts in opposite directions simultaneously.

6. Apparatus for clearing and cleaning yarns, said apparatus comprising a rotary shaft, circular knives mounted upon the said shaft to rotate therewith, a second rotary shaft parallel to the first and having circular knives mounted thereon to rotate therewith, the periphery of any circular knife on one shaft overlapping the periphery of a circular knife on the other shaft with a space for yarn to pass between the overlapping portions of the knives for the clearing or cleaning of said yarn, bearings for the shafts, means for rotating the two shafts in opposite directions simultaneously, means for longitudinal adjustment of one on the shafts to vary the space between any circular knife on said shaft and its co-acting knife on the other shaft, a housing for one end of said other shaft, a collar on the end of said other shaft, and a spring controlled plug within the housing to press the said collar against the ball bearing fitted between itself and the inner wall of the housing to keep the shaft in position longitudinally whilst allowing of its free rotation.

In witness whereof I have hereunto set my hand.

JOHN HENRY MARSH.
